Application November 16, 1944, Serial No. 563,731

14 Claims. (Cl. 122—504)

1

This invention relates to electronic devices and to a method for operating such devices, and more particularly to industrial control systems of this type which operate with gas-filled electron discharge tubes.

It is one of the main objects of the present invention to provide devices of this type which have very high sensitivity although they are extremely simple, this object being attained not by combining several amplification stages or more or less complicated circuit arrangements, but by a peculiar mode of operation of a gas discharge tube. Other objects are to provide such devices which lend themselves for selective control by several detecting impedances, and which furnish ample current for the safe operation of a load in the output circuit of a gas discharge tube; to provide devices of this type which operate in response to several detecting or control impedances which are completely isolated from each other; to provide circuits of this type which can be safely operated under the control of phototubes including gas-filled phototubes; to provide a method for operating gaseous or glow discharge tubes with a very high degree of sensitivity due to much-reduced starting current; and generally to provide circuits containing a gas discharge tube as a control element, and a method for operating such circuits, which are highly sensitive, economical in operation and yet simple and reliable.

It is well known that in order to initiate current flow between the main electrodes of a gas discharge tube, a voltage and a current flow of certain values must exist between cathode and starting electrode. If either one of these values prevails without the other, starting ionization sufficient to initiate the main discharge will not be provided.

It has heretofore been presumed that the flow (this concept being herein used in the conventional sense, from anode to cathode, opposite to the electron flow) of starting current must proceed from the starting electrode to the cathode, or in other words that in order to start the gas discharge tube, the starting electrode must be more positive than the cathode, so that, in order to initiate breakdown and conductivity of the tube, the potential of the starting electrode must be made more positive relatively to the cathode.

I have found that all three-element cold-cathode gas-filled tubes commercially available to me at the present time can be rendered conductive while the starting or auxiliary electrode is more negative than the cathode, so long as

the necessary starting current and voltage values are present. With this mode of operation, the starting electrode operates so to speak as a starting cathode, with the cathode acting as an anode, whereas, as soon as the starting ionization is reached, the cathode assumes its regular function of providing for current flow thereto from the main anode. Circuits incorporating this principle of starting a gas-discharge tube are especially advantageous because the ionization current required for causing transition from starting to main discharge is with this mode of operation much less, sometimes as low as one hundredth, of that necessary when the starting current flows to the cathode from a more positive starting electrode. Therefore, a tube operated in this manner, namely by rendering, for starting the tube, the auxiliary electrode potential more negative relatively to the cathode, is much more sensitive as compared to its conventional use with an auxiliary electrode that is, during the starting period, more positive relatively to the cathode.

These and other objects, aspects and features 25 of the present invention will be more fully apparent from the following description of several practical embodiments illustrating the genus of the invention. This description refers to a drawing in which

30 Figs. 1 and 3 are circuit diagrams illustrating the basic principle of the present circuit, for operation with direct current and alternating current, respectively;

35 Figs. 2 and 4 are diagrams illustrating the operation of circuits according to Figs. 1 and 3 respectively;

Fig. 5 is the circuit diagram of a burner control installation incorporating a circuit according to the invention; and

40 Fig. 6 is a diagram similar to Figs. 2 and 4, illustrating operation with starting current whose phase is shifted relatively to the anode voltage.

In Fig. 1, letters A and B indicate two terminals or wires supplied with direct current. A potential apportioning device such as potentiometer R is connected across wires A and B. A gas-filled electron discharge tube K, with anode a, cathode k, and starting electrode i is connected between terminal A and the tap b of potentiometer R.

50 An operator load Z¹, such as the magnet of a relay switch is inserted in the output circuit of tube K. A normally closed restoring switch, such as push-button switch s is provided in the output circuit of tube K, for example between cathode k and adjustable tap b.

The starter electrode i is connected, in a starting circuit N , to an adjustable tap d of potentiometer R , which tap d provides a potential which is lower than that derived from tap b supplying cathode k . Between electrode i and tap d is connected a control or detecting impedance Z_2 , indicated in Fig. 1 as an adjustable resistor. In series with the detecting impedance may be connected a limiting resistance R_1 . A bypass capacitor C may be connected between electrode i and wire B .

This arrangement operates as follows.

Under operating conditions with Z_1 deenergized, which condition may be considered normal, detecting impedance Z_2 is high enough to limit the current which may flow between electrode i and cathode k to a value which is below that able to provide ionization sufficient to cause breakdown of tube K and conductivity between cathode k and anode a . The voltage between electrode i and cathode k , with i having a potential more negative than that of k due to the above-mentioned arrangement of taps b and d , may or may not be that required for causing the minimum ionization necessary for starting the tube.

If the impedance Z_2 now decreases sufficiently to permit increased flow in circuit

A—b—s—k—i—Z2—R1—d—B,

and if this increased current reaches the starting ionization value, the space between i and k will be sufficiently ionized to initiate gaseous discharge between the main electrodes of tube K . The voltage between i and k may or may not increase when the current flowing between i and k increases, but at any rate the potential of i will be more negative than that of k . As well known, tube K will remain conductive, regardless of the condition of auxiliary electrode i . In order to restore tube K to nonconducting condition, restoring switch s has to be opened in order to interrupt the output circuit of tube K . If, upon reclosing the restoring switch s , the starting circuit N is still in starting condition, tube K will again become conductive.

The above-described operation is further explained in diagram Fig. 2 which, considering the legends applied to its various curves, will now be self explanatory. Attention is especially called to the starter anode current which increases in negative direction, that is in the conventional flow direction from cathode k to electrode i , until the tube breaks down, whereupon current begins to flow in the usual direction from anode a to cathode k . It will be understood that in a diagram of this type, the transient configurations can be reproduced only with an accuracy sufficient to indicate the qualitative character of the operation.

Fig. 3 illustrates an arrangement quite similar to that of Fig. 1, but for alternating current operation. In this figure, D and F are supply terminals or wires connected to an alternating current source. A transformer L is with its primary L_1p connected across wires D and F . The gas-discharge tube K , with operator load Z_1 in its output circuit, is connected between the high potential terminal e of transformer L and wire D . The starting electrode i is connected to the low potential terminal f of transformer secondary L_1s , through a detecting impedance Z_2 and a limiting resistor R_1 . This figure indicates the possibility of varying impedance Z_2 by means of a starting switch S bridging Z_2 and for example normally

open. Impedance Z_2 may also be a phototube with its anode connected to i and its cathode to R_1 , as in the embodiment to be described with reference to Fig. 5. A bypass capacitor C is preferably connected between electrode i and wire F .

The windings of transformer L are so arranged that the voltages in primary L_1p and secondary L_1s are 180° out of phase, so that electrode i will be negative when wire D and anode a of tube K are positive.

The arrangement according to Fig. 3 operates as follows.

Again considering first the condition when tube K is nonconductive, the current which may flow between auxiliary electrode i and cathode k is insufficient to ionize tube K sufficiently for breakdown and Z_1 is deenergized.

If impedance Z_2 is now decreased, for example by closing switch S , the negative peak potential reached by auxiliary electrode i will, during the half cycle in question, reach a value which, together with a simultaneous positive potential of anode a , causes current flow from k to i sufficient to ionize the tube for breaking it down and starting the main discharge between k and a . It will be evident that impedance Z_2 together with switch S could be replaced by a continuously variable detecting impedance as shown in Fig. 1.

The resistor R_1 has the purpose of limiting the starting current between k and i to harmless values, if the detecting or starting impedance Z_2 should assume a very low value.

The above-described operation will be better understood with the aid of diagram Fig. 4 which is analogous to that of Fig. 2 and which indicates clearly that with increased negative potential of electrode i , and increased current between k and i the tube becomes ionized between i and k , causing it to break down for gaseous discharge between k and a .

Fig. 5 illustrates the application of a circuit according to Fig. 3 to a flame supervising installation which is somewhat similar to that disclosed in Patent No. 2,358,432 to William F. Wolfner II, dated September 19, 1944.

In this figure D and F are again the terminal wires of an alternating current source. The primary L_1p of a starter transformer L_1 is connected between wires D and F . One terminal of the transformer secondary L_1s is connected to a wire m which may lead to one probe terminal, in the present instance the grounded boiler of a heating installation which will be described in detail hereinbelow. The grounded connection m may be joined to supply wire F . The other terminal of the transformer secondary L_1s is connected through a resistor R_2 to one terminal of the secondary L_2p of a second starter transformer L_2 . The other terminal of the transformer primary L_2p is connected through a capacitor C_2 to a second probe terminal n which, as indicated in Fig. 5, may be connected to a water level probe p . One terminal of transformer secondary L_2s may be connected to the grounded supply wire F . The other terminal of transformer secondary L_2s is connected to the cathode k_p of a phototube P .

A gas-discharge tube K is connected across terminal wires D and F , through relay magnet M which may operate a switch s_1 that is held open while M is energized. Magnet M is in the usual manner bridged by a sustaining capacitor C_3 in series with a resistor R_3 . The starter electrode i of tube K is connected to the anode a_p of photo-

tube P through a limiting resistor R4. A bypass capacitor C4 is connected between electrode i and terminal wire F.

The gap G formed between ground and probe p, and phototube P constitute a first and second variable detecting impedance, connected in a first and second starting circuit N1 and N2, respectively.

As indicated above, probe p is arranged to supervise the level of the water in a boiler schematically indicated at 10 of Fig. 5. A normal water level 11 connects terminal m of transformer secondary L1s to transformer primary L2p, in circuit

Ground—10—m—L1s—R2—L2p—
C2—n—p—11—10—ground

The boiler 10 may be equipped with a burner 15, for example a gas burner supplied through a valve 16 controlled by an operator 17 which is energized through switch s1, controlled by relay magnet M as above described. The phototube P observes the flame 20 through a suitably arranged supervising tube 21 directed at flame 20.

The arrangement according to Fig. 5 operates as follows.

Under normal operating conditions, valve 16 must be open, with switch s1 open and magnet M energized. Transformers L1 and L2, connected in circuits N1 and N2 including the closed probe connection from m to n through G apply the proper polarizing voltage to phototube P. It will be observed that, contrary to known arrangements as for example that described in the above-mentioned patent to William F. Wolfner, the phototube anode ap is connected to the starter electrode i of gas tube K. This arrangement conforms with that of the transformers L1 and L2 which, as described with reference to Fig. 3, are so connected that electrode i is negative during the half cycle when anode a of tube K is positive. The starting current flows accordingly in circuit F—k—i—R4—ap—kp—L2—L1—D, with k more positive than i and ap more positive than kp. With flame 20 illuminating phototube P, the latter is sufficiently conductive to supply to tube K the necessary starting current. Under these operating conditions, tube K is therefore conductive and M energized as above presumed.

If the water level should fall below probe p the connection between transformers L1 and L2 is interrupted, the voltage supplied to phototube P becomes insufficient for its operation, the current through electrode i falls below the minimum starting value, and tube K becomes nonconductive.

If the flame 20 should become extinguished, the conductivity of phototube P decreases so that sufficient starting current is not supplied to starter electrode i and cathode k, as above explained.

It will be evident that either abnormal water level or extinction of flame 20 causes tube K to become nonconductive and magnet M deenergized, closing switch s1. This may cause ringing of alarm bell 30 and closing of valve 16 or any other appropriate chain of operations, for example including the starting of a feedwater pump. Upon restoration of normal operating conditions either by hand or automatically with well-known means, that is when the water level again reaches probe p and flame 20 is again burning, the voltage and current values necessary for starting tube K will again be applied to starter electrode i and

the system is again in normal operating condition as indicated in Fig. 5.

If a high vacuum phototube is used, there exists little danger that the voltage surge, which occurs when the tube K breaks down and the starter electrode suddenly assumes a positive potential, will injure the phototube. However, it may be advisable to use limiting resistors R2 and R4, or at least one of these, in order to limit the phototube current to a safe value, especially if the phototube is of the gas-filled type. In the latter instance the phototube might become ionized when the starter electrode is drawn positive by the discharge right after starting.

15 In order to assure safe operation of relay magnet M, it may be advisable to use, in accordance with one of the aspects of the invention, the following arrangement of the starter electrode circuit.

20 A capacitor C2 is inserted in the circuit connecting the two transformers, which causes the alternating current supplied through starter electrode i to be somewhat advanced in phase as compared to the voltage supply of anode a. As 25 illustrated in Fig. 6, this provides starting conditions before the main wave reaches its peak value, so that magnet M is supplied with current during a considerable period of the positive half cycle.

It should be understood that the present disclosure is for the purpose of illustration only and that this invention includes all modifications and equivalents which fall within the scope of the appended claims.

I claim:

35 1. The method of operating a gaseous discharge tube having anode, cathode and starter electrode of the type wherein the starter electrode is normally used for effecting a starting discharge between said starter electrode and said cathode, characterized by applying to said electrode, for starting the tube, a potential that is negative with regard to that of said cathode and current sufficient to ionize a path between said electrode and said cathode while they act as 40 starter cathode and anode, respectively, but not sufficient to ionize a path between said electrode and said anode, whereupon the main current path between said anode and said cathode becomes established with current flowing in the 45 substantially fully ionized gas between said anode and said cathode.

2. The method of operating a gaseous discharge tube having anode, cathode and starter electrode of the type wherein the starter electrode is normally used for effecting a starting discharge between said starter electrode and said cathode, characterized by applying to said electrode while the tube is in normal nonconductive condition, a potential that is more negative than 55 that of the cathode and, for starting the tube, by applying to said electrode a negatively increased potential and current sufficient to ionize a path between said electrode and said cathode while they act as starter cathode and anode, respectively, but not sufficient to ionize a path between said electrode and said anode, whereupon the main current path between said anode and said cathode becomes established with current flowing in the substantially fully ionized gas 60 between said anode and said cathode.

3. An arrangement for operating electronic control circuits including a gaseous discharge tube with anode, cathode and starter electrode of the type wherein the starter electrode is normally used for effecting a starting discharge be- 70

75

tween said starter electrode and said cathode, comprising means for applying an operating voltage to said anode and said cathode, starting circuit means for applying to said electrode a potential that is negative with respect to the potential of said cathode and which provides a current path through said electrode and said cathode, and means for causing said starting circuit means to carry current flowing from said cathode to said electrode and adapted to ionize gas in the tube sufficiently between said cathode and said electrode to cause the tube to become conductive with current flowing from said anode to said cathode.

4. An arrangement for operating electronic control circuits including a gaseous discharge tube with anode, cathode and starter electrode of the type wherein the starter electrode is normally used for effecting a starting discharge between said starter electrode and said cathode, comprising means for applying an operating voltage to said anode and said cathode, starting circuit means for applying to said electrode a potential that is negative with respect to the potential of said cathode and which provides a current path through said electrode and said cathode, and means for negatively increasing said starter electrode potential and causing said starting circuit means to carry current flowing from said cathode to said electrode and adapted to ionize gas in the tube sufficiently between said cathode and said electrode to cause the tube to become conductive with current flowing from said anode to said cathode.

5. An arrangement for operating electronic control circuits including a gaseous discharge tube with anode, cathode and starter electrode of the type wherein the starter electrode is normally used for effecting a starting discharge between said starter electrode and said cathode, comprising means for applying an operating voltage to said anode and said cathode, and starting circuit means including means for applying to said electrode a potential that is negative with respect to the potential of said cathode and a phototube whose anode means is connected to said electrode and which provides a current path through said electrode and said cathode, said phototube when illuminated to a predetermined degree passing an amount of current through said path and from said cathode to said electrode which in the presence of said negative potential ionizes gas in said discharge tube sufficiently between said cathode and said electrode to cause the gaseous discharge tube to become conductive with current flowing from said anode to said cathode.

6. An arrangement for operating electronic control circuits including a gaseous discharge tube with anode, cathode and starter electrode of the type wherein the starter electrode is normally used for effecting a starting discharge between said starter electrode and said cathode, comprising means for applying a unidirectional operating voltage to said anode and said cathode, and starting circuit means including voltage apportioning means and a variable detecting impedance for applying to said electrode a potential that is negative with respect to the potential of said cathode and which provides a current path through said electrode and said cathode, said detecting impedance when reduced to a predetermined value negatively increasing said starter electrode potential and causing said starting circuit means to carry current flowing

7. An arrangement for operating electronic control circuits including a gaseous discharge tube with anode, cathode and starter electrode of the type wherein the starter electrode is normally used for effecting a starting discharge between said starter electrode and said cathode, comprising means for applying an alternating operating voltage to said anode and said cathode, and starting circuit means including transformer means and a variable detecting impedance for applying to said electrode a potential that is negative with respect to the potential of said cathode and which provides a current path through said electrode and said cathode, said detecting impedance when reduced to a predetermined value negatively increasing said starter electrode potential and causing said starting circuit means to carry current flowing from said cathode to said electrode in sufficient quantity in the presence of said negatively increased potential to ionize gas in said tube sufficiently between said cathode and said electrode to cause the tube to become conductive with current flowing from said anode to said cathode.

8. An arrangement for operating electronic control circuits including a gaseous discharge tube with anode, cathode and starter electrode of the type wherein the starter electrode is normally used for effecting a starting discharge between said starter electrode and said cathode, comprising connecting means for applying a unidirectional operating voltage to said anode and said cathode, starting circuit means including voltage apportioning means and a variable detecting impedance for applying to said electrode a potential that is negative with respect to the potential of said cathode and which provides a current path through said electrode and said cathode, said detecting impedance when reduced to a predetermined value negatively increasing said starter electrode potential and causing said starting circuit means to carry current flowing from said cathode to said electrode in sufficient quantity in the presence of said negatively increased potential to ionize gas in said tube sufficiently between said cathode and said electrode to cause the tube to become conductive with current flowing from said anode to said cathode.

9. An arrangement for operating electronic control circuits including a gaseous discharge tube with anode, cathode and starter electrode of the type wherein the starter electrode is normally used for effecting a starting discharge between said starter electrode and said cathode, comprising means for applying an alternating operating voltage to said anode and said cathode, and starting circuit means including transformer means for applying to said electrode a potential that is negative with respect to the potential of said cathode and a phototube whose anode means is connected to said electrode and which provides a current path through said electrode and said cathode, said phototube when illuminated to a predetermined degree passing an amount of current through said path and from said cathode to said electrode which in the presence of said negatively increased potential to ionize gas in said tube sufficiently between said cathode and said electrode to cause the tube to become conductive with current flowing from said anode to said cathode while said interrupting means remains closed.

10. An arrangement for operating electronic control circuits including a gaseous discharge tube with anode, cathode and starter electrode of the type wherein the starter electrode is normally used for effecting a starting discharge between said starter electrode and said cathode, comprising connecting means for applying a unidirectional operating voltage to said anode and said cathode, starting circuit means including voltage apportioning means and a variable detecting impedance for applying to said electrode a potential that is negative with respect to the potential of said cathode and which provides a current path through said electrode and said cathode, said detecting impedance when reduced to a predetermined value negatively increasing said starter electrode potential and causing said starting circuit means to carry current flowing from said cathode to said electrode in sufficient quantity in the presence of said negatively increased potential to ionize gas in said tube sufficiently between said cathode and said electrode to cause the tube to become conductive with current flowing from said anode to said cathode.

ence of said negative potential ionizes gas in said discharge tube sufficiently between said cathode and said electrode to cause the gaseous discharge tube to become conductive with current flowing from said anode to said cathode.

10. An arrangement for operating electronic control circuits including a gaseous discharge tube with anode, cathode and starter electrode of the type wherein the starter electrode is normally used for effecting a starting discharge between said starter electrode and said cathode, comprising means for applying an alternating operating voltage to said anode and said cathode, and starting circuit means including transformer means and a variable detecting impedance for applying to said electrode a potential that is negative with respect to the potential of said cathode and which provides a current path through said electrode and said cathode, said transformer means being so constructed and arranged that the phase of the voltage applied from the transformer means to said electrode leads that applied from the source to said anode, and said detecting impedance when reduced to a predetermined value negatively increasing said starter electrode potential and causing said starting circuit means to carry current flowing from said cathode to said electrode in sufficient quantity in the presence of said negatively increased potential to ionize gas in said tube sufficiently between said cathode and said electrode to cause the tube to become conductive with current flowing from said anode to said cathode, said phase shift causing the tube to become conductive before the peak of the anode voltage is reached and hence providing increased periods of conductivity of the tube.

11. An electronic control circuit comprising a gaseous discharge tube with anode, cathode and starter electrode of the type wherein the starter electrode is normally used for effecting a starting discharge between said starter electrode and said cathode; an alternating current source arranged for applying an operating voltage to the load circuit including said anode and said cathode; operator means in said load circuit; a first and a second detecting impedance; a first starting circuit connected for energization from said source and including said first detecting impedance; a second starting circuit including in series connection said second detecting impedance, said starter electrode and said cathode; and means for electrically coupling said starting circuits; said starting circuits being arranged for applying to said electrode a potential that is negative with respect to the potential of said cathode and which provides a current path through said electrode and said cathode, and, upon change of the value of one of said detecting impedances, for negatively increasing said starter electrode potential and causing said second starting circuit to carry current flowing from said cathode to said electrode and adapted to ionize gas in the tube sufficiently between said cathode and said electrode to cause the tube to become conductive with current flowing from said anode to said cathode.

12. An electronic control circuit comprising a gaseous discharge tube with anode, cathode and starter electrode of the type wherein the starter electrode is normally used for effecting a starting discharge between said starter electrode and said cathode; an alternating current source arranged for applying an operating voltage to the load circuit including said anode and said cath-

ode; operator means in said load circuit; a first and a second starter transformer; a first and a second detecting impedance; means for connecting the primary of said first transformer to said source; a first starting circuit including in series connection the secondary of said first transformer, said first detecting impedance, and the primary of said second transformer; and a second starting circuit including in series connection the secondary of said second transformer, said second detecting impedance, said starter electrode and said cathode; said starting circuits being arranged for applying to said electrode a potential that is negative with respect to the potential of said cathode and which provides a current path through said electrode and said cathode, and, upon change of the value of one of said detecting impedances, for negatively increasing said starter electrode potential and causing said second starting circuit to carry current flowing from said cathode to said electrode and adapted to ionize gas in the tube sufficiently between said cathode and said electrode to cause the tube to become conductive with current flowing from said anode to said cathode.

13. An electronic control circuit comprising a gaseous discharge tube with anode, cathode and starter electrode of the type wherein the starter electrode is normally used for effecting a starting discharge between said starter electrode and said cathode; an alternating current source arranged for applying an operating voltage to the load circuit including said anode and said cathode; operator means in said load circuit; a first and a second starter transformer; a first and a second detecting impedance; means for connecting the primary of said first transformer to said source; a first starting circuit including in series connection the secondary of said first transformer, a limiting resistor, said first detecting impedance, a capacitor and the primary of said second transformer; a second starting circuit including in series connection the secondary of said second transformer, a limiting resistor, said second detecting impedance, said starter electrode and said cathode; and a capacitor bridging the gap between said electrode and said cathode; said starting circuits being arranged for applying to said electrode a potential that is negative with respect to the potential of said cathode and which provides a current path through said electrode and said cathode, and, upon change of the value of one of said detecting impedances, for negatively increasing said starter electrode potential and causing said second starting circuit to carry current flowing from said cathode to said electrode and adapted to ionize gas in the tube sufficiently between said cathode and said electrode to cause the tube to become conductive with current flowing from said anode to said cathode.

14. An electronic circuit for controlling combustion equipment including fuel supply means for heating a body of material, comprising a gaseous discharge tube with anode, cathode and starter electrode; an alternating current source arranged for applying an operating voltage to the load circuit including said anode and said cathode; operator means in said load circuit adapted to control said fuel supply means; a first and a second starter transformer; a phototube arranged for supervising the combustion of said fuel; probe impedance means for supervising the condition of said material; means for connecting the primary of said first transformer to said source; a first starting circuit including in series

connection the secondary of said first transformer, a limiting resistor, said probe impedance means, a quantity of said material, and the primary of said second transformer; and a second starting circuit including in series connection the secondary of said second transformer, a limiting resistor, said phototube, said starter electrode and said cathode; said starting circuits being arranged for applying to said electrode a potential that is negative with respect to the potential of said cathode and which provides a current path through said electrode and said cathode, and, upon change of the conductivity of said phototube or said probe means, for negatively increasing said starter electrode potential and causing said second starting circuit to carry current flowing from said cathode to said electrode, whereby said tube is rendered conductive to energize said

fuel supply means, and said fuel supply means is controlled by the condition of either said combustion or said material.
